TAPE CONTROLLED TELEGRAPH TRANSMITTER

Application filed December 23, 1930, Serial No. 504,256, and in Great Britain February 12, 1930.

This invention relates to telegraph transmitters in which a perforated tape is utilized to control the movements of a contact lever, and more particularly to telegraph transmitters of this class in which small light fingers, hereinafter referred to as peckers, are arranged to co-operate with signal perforations in the tape to control signalling contact means in accordance therewith.

In telegraph transmitters of this type the peckers may be of trailing form in which after entry into a perforation the edge of the perforation itself moves the pecker away by moving against the inclined trailing tip, but a more usual arrangement is to move the pecker positively in one direction away from the perforated tape by means such as a cam or eccentric geared to the means which moves the tape. The cam or eccentric then permits the pecker to rise under spring action and this movement is permitted by a perforation, or obstructed by blank tape at this point. In such cases a signalling contact lever is maintained on one contact screw if blank tape is encountered but if a perforation occurs the contact lever is actuated over to another contact screw. By this means, signals are sent to line in accordance with the position of perforations in a tape.

Many arrangements of signalling means of this kind are known as adapted to suit different codes and methods of signalling, either one or a number of peckers may co-operate with one or a number of series of perforations in a tape to actuate a corresponding contact lever or series of such levers. Alternatively a number of peckers may actuate a single contact lever or a number of such levers less in number than the peckers.

In telegraph transmitters of this class, the force available to actuate the contact lever by the direct action of the pecker is relatively feeble, as the spring tension or equivalent force which may be applied to the pecker so as to enable it to enter a perforation, but yet not to pierce or unduly strain the tape if a blank portion intervenes, is very limited. Arrangements have therefore been devised whereby the movements of the peckers are caused to effect a selecting movement only,

the actual operation of moving the contact lever being performed by mechanical power. At high signalling speeds of these known arrangements, however, considerable bounce of the contact lever on the contact screws takes place at each actuation and increases the apparent transit time of the contact lever.

According to the present invention a telegraph transmitter in which peckers co-operate with signal perforations in a tape to control the movements of signalling contact means, is characterized in that the peckers control the rotation of a mechanically driven member which member effects the movement of the signalling contact means. A transmitter according to the present invention can therefore be considered to incorporate an arrangement sometimes referred to as a mechanical relay.

The term mechanical relay in this connection may be understood to include all those forms of mechanism in which alternating and intermittent movements of a control member are utilized to control the escapement or detent of a clutch of which the driving member is rotated by mechanical power, and in which an eccentric, cam or the like on the driven member of said clutch effects movement of a second member under the control of the said control member. The chief advantage of the incorporation of an arrangement of the type in the present invention may be said to reside in the nature of the force which maintains the contact means in the position to which it has been actuated, thus opposing any tendency to bounce, in addition to effecting the actual movements of the signalling contact means by mechanical power. The eccentric or cam on the intermittently rotatable driven member of the clutch permits less tendency to bounce of the movable contact means.

The clutch in a mechanical relay of this description may conveniently be formed as a plain friction clutch of which the driven member is arrested by an escapement or detent engaging a tooth formed thereon, but for the purposes of the present invention the preferred form of mechanical relay is that shown and claimed in our co-pending ap-

lication No. 484,074, now Patent No. 1,855,204, granted April 26, 1932. In this case the thrusts resulting from the load are utilized to increase the frictional contact of the driving surfaces of a friction clutch. This renders the action more positive and for a given load permits a great reduction in the dimensions and mass of the moving parts, which renders the arrangement very applicable to 10 high speed operation under the control of small forces as in the present invention.

It will be understood, however, that the invention is not limited to this particular form of mechanical relay nor to the particular 15 telegraph transmitters hereinafter described. The invention will be seen to be applicable to all types of telegraph transmitters in which signalling contact means is actuated in accordance with signal perforations 20 in a tape.

In the accompanying drawing, Figure 1 represents diagrammatically by way of example a transmitter according to the present invention adapted for operation under control of a tape perforated according to the Morse land line code whilst Figure 2 represents diagrammatically the application of the invention to a five-unit code transmitter.

Referring to Figure 1, a shaft 1 driven by 30 a motor (not shown) at a constant speed, moves the tape forward a distance of one centre hole for one revolution of shaft 1. Two eccentrics or cams 2 and 3 are disposed on shaft 1 at 180 degrees to each other and 35 alternately depress the two peckers 4 and 5 through bell-crank arms 6 and 7. The peckers 4 and 5 are arranged to rise alternately under the tension of springs 8 and 9 against the paper tape as cams 2 and 3 rotate. When 40 the pecker rises through a perforation in the tape, a corresponding bell crank lever 10 or 11, rotates a sufficient angle about its corresponding pivot 12 or 13 for a detent formed at the extremity of the upright arm of each bell crank, to release tooth 14 of the driven member of a friction clutch, the driving member of which is shown as shaft 1. The driven member of the clutch which carries tooth 14 and eccentric 15 has a cylindrical surface rotatably fitting in a sleeve-like extension of a driving shaft as shown and described in detail in the co-pending application Serial No. 484,074 hereinabove referred to. The two 45 detents formed at the extremities of the said upright arms of bell crank levers 10 and 11 are arranged to arrest tooth 14 at 180 degrees difference of phase. It is not essential that this driving member of the clutch of the mechanical relay should rotate at the same speed 50 as eccentrics or cams 2 and 3, but it should not rotate at a lower speed. The driven member is rotated and the eccentric pin 15 carries the contact lever 16 firmly over to the opposite position, the contact on the tongue making 55 contact with the opposite screw 17 or 18.

It will thus be seen that if a tape containing continuous Morse dots is passing through the transmitter the eccentrics or cams 2 and 3 will alternately oscillate the peckers 5 and 6 through the perforations in the tape and the driven member 19 of the clutch will rotate and contact lever 16 will make contact alternately with contacts 17 and 18. As soon as a pecker encounters blank tape the corresponding detent on upright arm or levers 10 and 11, is maintained in a position to arrest tooth 14, and contact lever 16 is maintained to one side or the other according to whichever pecker is impeded.

Figure 2 shows the manner in which a set 80 of cyclic cams 20-24 acting directly on the pecker levers 26-30 operates a single lever 32 controlling signalling contact means in a manner under control of a tape perforated according to a five unit code.

In the present invention lever 32 instead of forming a contact lever, as in the known arrangements forms the escapement release of a mechanical relay. It is only necessary in this case to rotate the driving member of 90 the clutch of the mechanical relay at a speed which is not less than the signalling impulse speed.

It is thought that the application to any other form of telegraph transmitter in which 95 a contact lever is to be actuated in accordance with the perforations in a tape will now be readily comprehended.

What is claimed is:

1. A tape controlled telegraph transmitter 100 having in combination, a pecker co-operable with a perforated tape, a rotatable driving member, a rotatable member driven thereby, a detent holding the driven member against rotation and actuated according to the movements of said pecker to release the driven member for rotation, and signal contact means actuated by said driven member in accordance with the movements of said pecker.

2. A tape controlled telegraph transmitter 110 comprising pecker means co-operable with signal perforations in a tape, detent means actuated by said peckers, a continuously rotatable driving member, a driven member controlled by said detent means, and signal contact means actuated from one position to another at each movement of said driven member.

3. A tape controlled telegraph transmitter 120 comprising pecker means co-operable with signal perforations in a tape, means to feed tape, means to permit said peckers to rise into operative relation with successive portions of said tape, detent means actuated by said pecker means on entry into a perforation, a continuously rotatable driving member, a driven member released for rotation of a pre-determined amount on actuation of said detent means, and signal contact means actuated by said driven member.

4. In a tape controlled telegraph transmitter, pecker means co-operable with signal perforations in a tape, detent means controlled thereby, a continuously rotatable member having a concentric frictional driving surface, a driven member controlled by said detent means and having a corresponding concentric frictional surface engaging with said driving member, an eccentric on 10 said driven member, and signal contact means actuated therefrom.

5. In a telegraph transmitter adapted to operate under control of a tape perforated according to the Morse land line code, two 15 independent peckers operable respectively with different series of signal perforations in a tape, two corresponding detents controlled by said peckers, a rotatable member having a tooth engageable alternately with one and 20 the other of said detents at each half revolution driving rotation and signal contact means actuated from one position to another at each half revolution of said rotatable member.

25 6. In a telegraph transmitter adapted to operate under control of a tape perforated according to a five unit code, a series of five independent peckers each co-operable with one of a series of corresponding signal perforations in a tape, means to bring said peckers sequentially into operative relation with said series of signal perforations, a single escapement member, actuated by any said pecker, a rotatable member controlled by said 30 escapement, and signal contact means actuated thereby from one position to another.

7. A tape controlled telegraph transmitter having in combination, a pecker co-operable with a perforated tape, a rotatable driving 40 member, a rotatable member to be driven thereby when coupled thereto, a detent actuated according to the movements of said pecker to couple and decouple the driving and driven members, and signal contact 45 means actuated by said driven member in accordance with the movements of said pecker.

In witness whereof we hereunto subscribe our names this third day of December 1930.

FREDERICK GEORGE CREED.
REGINALD DENNIS SALMON.
